UNITED STATES PATENT OFFICE.

FRANK YOKEL, OF BUFFALO, NEW YORK, ASSIGNOR TO MARKEL ELECTRIC PRODUCTS, INC., OF BUFFALO, NEW YORK, A CORPORATION OF NEW YORK.

DESIGN FOR A WALL FIXTURE FOR ELECTRIC LIGHTS.

Application filed November 23, 1928. Serial No. 28,998. Term of patent 3½ years.

To all whom it may concern:

Be it known that I, FRANK YOKEL, a citizen of the United States, residing at Buffalo, in the county of Erie and State of New York, have invented a new, original, and ornamental Design for Wall Fixture for Electric Lights, of which the following is a specification, reference being had to the accompanying drawing, forming part thereof.

In said drawing:

Figure 1 is a front elevation of a wall fixture for electric lights embodying my new

design. In this figure half of the wall fixture is shown in full lines and the other half in outline in dot and dash lines to indicate the repetition of the pattern.

Figure 2 is a top plan view of the same, partly in full lines and partly in dot and dash lines.

I claim:

The ornamental design for a wall fixture for electric lights, substantially as shown and described.

FRANK YOKEL.
